Plant 7,620

3

Form.—Cupped.*Size*.—4.5–7.0 cm across open floret.*Lasting quality*.—Good; comparable to the cultivar 'Olga'.*Petals*:*Number*.—5–6.*Texture and appearance*.—Smooth.*Color*.—Upper petals: Adaxial: Margin: Red 39B.

Central spot: Greyed-purple 187A with orange-red 33B halo. Proximal veins and feathering:

Red-purple 59A. Base: White 155D. Abaxial:

Margin: Red 39B. Central spot: Greyed-purple

187A with orange-red 33A halo; slightly smaller than adaxial spot. Lower petals: Adaxial: Red 15

39B. Base: White 155D with infrequent light

feathering greyed-purple 183B and orange-red 33A. Abaxial: Red 50C. Base: White 155A.

Petaloids.—Number: 0 to 1. Shape: Petal-like.

Color: Similar to the color of the petals.

Sepals.—Number: 5–6.*Pedicel*.—Subtended by bracts. Length: 1.7 to 3.3 cm. Color: Yellow-green 144A.*Peduncle*.—Arises from node; opposed to leaf petiole; subtended by leaves and bracts. Length: 7.0 to 9.2 cm. Color: Yellow-green 144A.

4

Reproductive Organs

Androecium:*Stamens*.—7–9 flat, ribbon-like filaments, joined at their bases; upper $\frac{1}{3}$ of the filaments is pale purple; versatile attachment to anthers which are light purple and well developed; 2 sizes of orange pollen; anthers had a narrow extension at the tip of each anther.*Staminodes*.—3–4 flat, ribbon-like filaments with no anthers.*Petaloid stamens*.—None observed.*Gynoecium*:*Pistil number*.—1. Length: 11.5–16.0 mm. Stigma: 5–7-parted; purple. Style: 3.5–8.0 mm long; purple. Ovary: 4.0–5.0 mm long; superior; very pubescent.*Fruit*.—Schizocarp; rarely observed.

20 What is claimed is:

1. A new and distinct cultivar of regal Pelargonium substantially as illustrated and described herein, particularly characterized as being compact and self-branching, early flowering and floriferous, and having flowers which are light orange-red in color with red-purple feathering primarily on the upper petals.
